ELECTRICAL CONNECTOR ARRANGEMENT

Frank Edwin Baum, Amherst, Great Baddow, Chelmsford, England, assignor to Radio Corporation of America, a corporation of Delaware

Application January 20, 1938, Serial No. 185,800
In Great Britain January 21, 1937

10 Claims. (CL 173—324)

This invention relates to electrical connector arrangements and more particular to such arrangements for connecting apparatus in one body or container to apparatus in a second body or container which is required to have a rotary movement relative to the first. The principal application of the invention is to electrical connectors for use in tanks, armoured cars and the like for connecting apparatus in the main body or hull to apparatus in the rotary turret.

In practice, supplies which are frequently required to be brought from the hull of a tank to the turret are—

(1) Water supplies (flow and return) for cooling the gun;

(2) If (1) above is not required it is often required to carry an electric supply into the turret to operate a motor driven pump positioned therein and producing the necessary water circulation for the gun;

(3) A voice pipe for allowing conversation between a gunner situated in the turret and the driver in the hull; and

(4) Electrical supply for operation of wireless or radio apparatus and other purposes.

Where the second of the above requirements is present instead of the first, the wireless or radio supply cables may also be utilized for carrying the electric current to work the pump.

A difficulty which arises in tanks and in other cases where it is required to carry supplies, including an electric supply from a main hull to a rotary turret or the like, is that the rotation of the turret produces a twisting action in the electrical connections and known apparatus for avoiding this difficulty is either undesirably complex or is not adapted to allow of a reasonably large number of supplies to be taken. The usual method employed hitherto in tanks consists in utilizing a rotary connector fixed to the floor of the hull as near as possible to the axis of rotation of the turret. This is reasonably satisfactory so long as only one supply is required, but where two or more supplies are required, the necessity for "duplicating" the rotary connector by one or more additional connectors all concentrically arranged involves complexity and mechanical inefficiency.

According to the main feature of this invention, an arrangement for carrying supplies, including at least one electric supply, from the hull of a tank (or some other relatively fixed body) to the turret of a tank (or some other relatively rotary body) is characterized in that the electrical supply connections between the relatively fixed and

the relatively rotary bodies include brush contact devices or the equivalent the leads to which are carried upon a member which is automatically rotated when relative rotation between the two said bodies takes place so that twisting of the connectors is avoided.

According to another feature of this invention, an arrangement for carrying supplies, including at least one electric supply, from the hull of a tank (or some other relatively fixed body) to the 10 turret of a tank (or some other relatively rotary body) is characterized in that the electrical supply connections between the relatively fixed and the relatively rotary bodies include slip ring contact devices or the equivalent, the leads to which 15 are carried upon a member which is automatically rotated when relative rotation between the two said bodies takes place so that twisting of the connectors is avoided.

A preferred embodiment of the invention for 20 use in a tank is illustrated in the accompanying drawings, in which:

Fig. 1 is a side elevation;

Fig. 2 is a front elevation;

Fig. 3 is a sectional view on the line 3—3 of Fig. 25 2 of the said embodiment;

Fig. 4 shows a sectional view of a portion of the 30 turret and tank hull to indicate the relative position of the connector arrangement of this invention;

Fig. 5 is a side elevation of another modified form of this invention;

Fig. 6 is a sectional view through the center of Fig. 5 and in a plane parallel to the paper; and

Fig. 7 is a sectional view of the turret and hull 35 portion showing the relative position of the connector arrangement of Figs. 5 and 6.

Referring first to Figs. 1, 2 and 3, an outer drum member 1 and a disc 8 constitute a structure or casing which, as a whole, is attached vertically in 40 any convenient way, as by means of a bracket, as a fixture to the rotary turret, so that this structure revolves as a whole with the turret about the center of rotation of the latter. The structure is so fixed to the turret that the drum 1 is relatively to the turret, a fixture but the disc 8 is adapted to rotate, relatively to drum 1 about its own center. The drum carries an insulated ring 2 to which are attached two contact rings 3 and 4. Circular disc-like brushes 5 carried on an insulating member 6 make contact with the rings 3, 4, the said brushes being constructed in any convenient manner known per se to give efficient electrical contact.

The insulating member 6 which is carried by 55

the "carrier disc" 8 is at one end a bearing fit in a circular slot 7 in the wall of the drum 1, the other end of the member 6 being a bearing fit in a disc member 8 hereinafter referred to as the "carrier disc."

The carrier disc 8 is actually formed as a spur gear, the teeth being indicated at 8a, and this gear is rotated concentrically on a center boss 1a formed on the drum 1, by means of a driving pinion 9 which is mechanically connected by a shaft 10 with a toothed wheel 11 which meshes at right-angles in the teeth of an internally cut gear wheel 12, the center of which is assumed to be at a point to the left of Fig. 3, fixed to the hull of the tank.

The water supply pipes for the gun (flow and return) come up from an axially positioned rotary connector of known construction (not shown) on the floor of the tank and pass at 1b through a central aperture in the drum 1, these pipes 13, 14, being uninterrupted where they pass through the drum 1. Twin cables for wireless (electrical) supplies are led up from their own rotary connector (not shown)—also of known construction and arranged on the floor of the tank—and are connected to the disc brushes. As shown, a flexible double conductor cable 15 is connected via a plug and socket arrangement 16 to the disc brushes 5. As will be apparent from the drawings, when the turret is rotated (this is accomplished in the ordinary way by means of handwheel H and pinion P fixed to the turret and working on the fixed internal gear 12) a circular movement is transmitted to the carrier disc 8 via the toothed wheel 11 and pinion 9 and these parts are so arranged that for one revolution of the turret about its axis, that is about the center of wheel 12, the carrier disc rotates once about its own axis, thus counteracting any tendency which the cable 15, water pipes 13, 14, and a voice pipe (referred to below) have to twist about each other. As the insulator 6 for the disc brushes is carried on the carrier disc 8, it revolves round the contact rings 3, 4 thus maintaining electrical connection whatever the relative positions of the carrier disc and drum. Furthermore, pins or studs 17 are provided at predetermined positions on the insulator 6 and on the wall of the drum 1 and thus cause rotation of the member 6 on its own axis. In this way, twisting of the cables is prevented and at the same time a self-cleaning or wiping action is obtained at the brush contacts.

18 represents the voice pipe inlet and 19 the voice pipe outlet. As will be seen, the voice pipe itself is a circular slotted tube carried by the drum 1, the inlet and outlet being diametrically opposite one another with respect to the slotted voice pipe, the former being fixed to the carrier disc 8 whilst the latter is fixed to the drum 1. The tube slot is plainly shown at 19a. A cowling 20 attached to the inlet 18 is fitted over the voice pipe slot. As the inlet is mechanically connected to the carrier disc 8, it will revolve with the turret and provide a continuous channel for the sound waves which will enter the voice pipe by means of the slot.

Although in Fig. 3 the voice pipe inlet is shown nearer the axis of the carrier disc than is the electric supply it could, if desired, be at the same or any other radial distance from the said axis.

To facilitate standardization of the apparatus for different tanks—it being assumed that all tanks have internally cut gears 12 of the same

tooth pitch, means are preferably provided for varying, from tank to tank, the travel of the carrier disc in dependence upon the size of the tank. A small tank may, therefore, be taken as a basis for standardization and cams such as 21 may be introduced on the internally cut gears 12 in the case of larger tanks, the purpose of the cam 21 being to throw the toothed wheel 11 out of mesh at predetermined positions and for sufficient space to allow only one complete revolution of the disc 8 to occur for one complete revolution of the turret in either direction. In order to render this "throw out" operation possible, the bearings 22 of the shaft 10 are spring loaded, a collar 23 between the bearings allowing the desired movement (which is pivotal about a point at 8a where the disc 8 and pinion 9 mesh) and "throw out" action.

In the modifications illustrated in Figs. 5 and 6, as also in the arrangements already described, it will be supposed that it is required to provide for the supplies of water for e. g. gun cooling, electric power for wireless and other purposes, and for voice, although, of course, any convenient number and nature of supplies may be provided for.

Referring to Figs. 5 and 6, 101 is a base in which are arranged flow and return chambers 101a and 101b, connections to these chambers being effected through junction pipes 102 and 103.

A vertical flow pipe 104 is welded concentrically within a return pipe 105, the latter of which is a bearing fit in casting 101. Pipe 105 is provided with holes 105a and 105b whereby a continuous flow of water into and out of the pipe 105 is effected. Special glands with locking rings at 106 (comprising special waterproof lining rings, wedge shape compression washers, compression springs, and locking rings) prevent leakage from either of the chambers 101a or 101b and chamber 101a is closed at the bottom by means of a plate 107 and gasket 108. The bottom gland ring is arranged to prevent any upward movement of pipes 104 and 105, and to prevent upward leakage into the electrical portion of the unit, a groove 101c in the base 101 is provided round pipe 105, draining holes or ducts 101d communicating with this groove.

A rotatable casting 109 is provided with flow and return chambers 109a and 109b, the latter communicating with pipe 105 by means of holes 105b therein. Junction pipes 110 and 111 communicate respectively with chambers 109a and 109b. Pipes 102, 103, 110 and 111 may be connected in any convenient manner, e. g. by screws with external supply pipes.

The casting 109 is provided also with a flange 109c within which is a split voice pipe 112, communicating with a voice pipe 113 leading into the turret. Around the shank of casting 109 are provided insulating rings 114 and 115 which carry slip rings 116a and 116b for the electric power supply. Connection to these slip rings is made through a plug 124 mounted on the flange 109c. Mounted on the base casting 101 is a plate 118 which carries leaf brush springs 117. These brushes 117 are provided with plugs 119 by means of which they are connected to an incoming supply socket 120 with which a spring clip 120a engages.

The voice pipe 112, within flange 109c, is held rigid by supports from plate 118 and an incoming pipe 121 which is carried in a bearing bush 122 on

plate 118. A spun cover 123 is fixed to the flange 108c to preclude the entry of dirt, etc.

In operation, water is pumped through pipes 102 into chamber 101a and via pipe 104 into chamber 109a whence it passes through pipe 110 away to, e. g. a gun. The return is from the gun through pipe 111 chamber 109b, the pipe hole 105b in pipe 105, by way of pipe 105, through a lower hole 105a, into chamber 101b and back to the supply through pipe 103. Conversation between the driver and an operator in the turret is effected by way of pipe 121, which is connected to pipe 112, then by way of pipe 112 and out to the operator by way of pipe 113. The electrical supply is connected by sockets 120 to plugs 119 and thence by way of brushes 117, slip rings 116a and 116b, to plug 124. The rotatable casting is driven from the turret by means of suitable projections or any other suitable means depending on the conditions under which the apparatus is operating so, that as the turret revolves, the casting 109 rotates with it and the various connections from this casting also revolve and thus obviate twisting or crossing of the connections.

The whole unit is rigid and compact and takes up very little room.

While in the drawings water, wireless supply and voice tube connections only have been shown, it will be appreciated that other supplies may be carried in like manner by means of a rotary connector arrangement in accordance with this invention.

What is claimed is:

1. A system for carrying fluid supplies including at least one electrical supply from a relatively fixed body to a relatively rotatable body comprising a casing having a drum portion and a disc portion, a fluid supply pipe passing through said casing, a plurality of collector rings for electrical supply connections arranged within said casing and secured to said drum portion, means for making electrical connection to said collector rings including a brush contact device within said casing and carried by said disc portion, a plurality of leads connected to and extending out of said casing from said brush contact device, and means engaging said disc portion to automatically rotate it when relative motion between the two said bodies takes place so that twisting of the leads for the electrical connections is avoided.

2. A system as claimed in claim 1, wherein said casing is fixedly attached as a whole to the relatively rotatable body, said rotatable body being adapted to be rotated relative to the disc portion of said casing about its own axis as said casing revolves around the center of rotation of said relatively rotatable body.

3. A system for carrying fluid supplies including at least one electrical supply from a relatively fixed body to a relatively rotatable body comprising a casing having a drum and a disc portion, a fluid supply pipe passing through said casing, a plurality of collector rings for electrical supply connections which are arranged within the casing and secured to said drum portion, means to make electrical connection to said collector rings including a brush contact device within said casing and connected by said disc portion, a plurality of leads connected to and extending out of said casing from said brush contact device, a rotatable member for rotating said disc portion, said drum portion being carried by said relatively rotatable body and adapted to be fixed relative to said disc portion and fixedly attached to said rel-

atively rotatable body, said drum portion having a bearing for a rotatable member to rotate said disc member.

4. A system for carrying fluid supplies including at least one electrical supply from a relatively fixed body to a relatively rotatable body comprising a casing having a drum and a disc portion, a plurality of collector rings for electrical supply connections arranged within the casing, means to make electrical connection to said collector rings including a brush contact device within said casing and carried by said disc portion, a plurality of leads connected to and extending out of said casing from said brush contact device for completing the electrical circuit from said rings to said electrical supply connections, a spur gear on said disc, driving means including a pinion with a bearing on said drum portion for cooperating with said spur gear to provide rotary movement of said disc portion as it is carried by said relatively rotatable body around the center of rotation thereof.

5. A system for carrying fluid supplies including at least one electrical supply from a relatively fixed body to a relatively rotatable body comprising a casing member having a drum and a disc portion, a plurality of electrical supply connections which are arranged within the casing, a plurality of collector rings within said casing, a brush contact device within said casing, a plurality of leads connected to and extending out of said casing from said brush contact device to make electrical connections from said collector rings to said electrical supply connections, a member comprising a spur gear carried by said drum portion, driving means including a pinion cooperating with said spur gear to provide rotary movement of said disc portion, and a shaft keyed to said pinion, said pinion engaging said spur gear with a gear fixedly attached to said relatively fixed body.

6. A system for carrying fluid supplies including at least one electrical supply as claimed in claim 3 wherein said casing is fixedly attached to said relatively rotatable body and comprises an annularly disposed voice channel wherewith inlet and outlet voice pipes communicate.

7. A system for carrying fluid supplies including at least one electrical supply from a relatively fixed body to a relatively rotatable body comprising a casing member having a drum and a disc portion, a plurality of collector rings for electrical supply connections which are arranged within the casing, a brush contact device within said casing, a plurality of leads connected to and extending out of said casing from said brush contact device, means to rotate said casing, an inlet voice pipe carried by the disc portion of said casing and cooperating with an annularly disposed voice channel located in the drum portion and provided with a slotted portion located adjacent said inlet voice pipe to complete the continuity of said voice pipe when said casing is rotated.

8. A system for carrying fluid supplies including at least one electrical supply from a relatively fixed body to a relatively movable body comprising a casing having a drum and a disc portion, fluid supply means passing through the center of said casing, a vocal tube located in said casing adjacent said fluid supply means, a plurality of collector rings within said casing and secured to be fixed relative to said disc portion, a plurality of brushes within said casing for making

electrical connection to said rings, and means to rotate said casing relative to said fixed body.

9. A system for carrying fluid supplies including at least one electrical supply from a relatively fixed body to a relatively movable body including the combination of a fluid supply tube, a vocal tube and electrical connection means all located within a casing, said casing divided into a fixed and a movable portion, and means external of said casing to connect said vocal tube and electrical connections from the movable portion of said casing to the fixed body.

10. A system for carrying fluid supplies in-

cluding at least one electrical supply from a relatively fixed body to a relatively movable body including the combination of a fluid supply tube, a vocal tube and electrical connection means all located within a casing, said casing being divided into a disc and a drum portion, means to rotate said disc portion with respect to said drum portion, and means external of said casing to connect said vocal tube and electrical connection from said disc and drum portion to said fixed body when relative motion is applied to said movable body.

FRANK EDWIN BAUM.
